UNITED STATES PATENT OFFICE

EMIL J. BERGER, OF HATFIELD, PENNSYLVANIA, ASSIGNOR TO DEXDALE HOSIERY MILLS, OF LANSDALE, PENNSYLVANIA, A CORPORATION OF PENNSYLVANIA

GARTER TOP STOCKING

Application filed August 18, 1931. Serial No. 557,807.

This invention relates to stockings with elastic garter tops, and also to methods of making such stockings.

Heretofore stockings of the type referred to were made by attaching to the tops of the otherwise finished stockings, elastic strip material, either by hand sewing or by over-edge stitching on seaming machines. The junctures thus made between the stocking fabric and the garters were bulky, unsightly and liable to interfere with the free stretch of both the stocking fabric and of the garter.

My invention has for its main object to overcome the drawbacks just referred to; and this desideratum I secure, as hereinafter fully set forth, by incorporating a length of elastic strip material incident to production of a stocking on a knitting machine, with attendant penetration of the elastic strip material along one edge by the course of loops along the top edge of the stocking leg. The juncture made under these conditions does not protrude beyond either face of the stocking, and therefore does not in any way mar the appearance of the stocking.

Also as hereinafter fully explained, my invention is adaptable to the manufacture of garter top stockings with welts, as well as stockings with plain knit upper leg portions.

Still other objects and attendant advantages will be manifest from the detailed description following when taken in connection with the attached drawings, wherein Fig. I illustrates a full-fashioned ladies' welt stocking conveniently embodying the incorporated garter top of my invention.

Fig. II shows diagrammatically a fragmentary sectional view at the region of junction of the garter top with the stocking, taken as indicated by the arrows II-II in Fig. I.

Fig. III is a fragmentary view, corresponding to Fig. I, showing an alternative form of my invention in which the garter material is concealed within the welt of the stocking.

Fig. IV is a fragmentary diagrammatic sectional view taken as indicated by the arrows IV-IV in Fig. III.

Fig. V is a view similar to Figs. I and

III showing the garter material incorporated in accordance with my invention, in a stocking devoid of a welt.

Figs. VI, VII, VIII and IX are diagrammatic illustrations showing successive steps 55 incident to the production of the garter top stocking shown in Figs. I and II on a full fashioned knitting machine.

Figs. X, XI, XII and XIII, in turn, show successive steps in the production of the 60 stocking of Figs. III and IV on a full fashioned knitting machine.

The stocking illustrated in Fig. I has the usual leg and foot portions 1 and 2, and a welt 3. The improved garter top of my invention is comprehensively indicated at 4, the same being formed from a woven strip 5 of elastic fabric with longitudinally extending rubber inlay yarns, and attached along one edge to the top edge of the welt 3 as a 65 consequence of penetration by the fabric loops along the fold line 6 of said welt. As conventionally indicated, this fold line 6 is, in the present instance, formed as a course of laterally-transferred or picot loops. By virtue of attachment of the elastic material 5 as described, the juncture 6 between the stocking welt 3 and the garter top 4 is absolutely flush, that is to say, without projection beyond either face of the stocking fabric. 70

The stocking illustrated in Fig. III is likewise of the full fashioned variety having a welt 3a at the top of its leg portion 1a, but in this case the elastic garter material 5a is concealed within the fold of the welt 3a. 75 Here again, however, the elastic strip material 5a, constituting the garter 4a, is edge attached along the line 6a of the fold of the welt 3a, which line, as in the type of stocking shown in Fig. I, may be formed as 80 a course of laterally-transferred or picot loops.

The stocking illustrated in Fig. V has a plain knit leg portion 1b with the elastic garter strip 5b attached through penetration 85 by the course of loops 6b along the top edge of the stocking fabric.

The manner in which I produce the stocking of Figs. I and II will be readily understood from Figs. VI-IX, the procedure being 100

as follows: I first impale one edge of the elastic strip material 5 upon the needles N of an ordinary flat knitting machine as in Fig. VI, with the aid of a topping bar (not shown), and incidentally depress the said strip material along the shanks of the needles N beneath the knock-overs K, or, in other words, below the knitting level. After knitting half the length 7 of the welt fabric as also shown in Fig. VI, I raise the elastic strip material 5 to the knitting level, i. e. between the sinkers S and the knockovers K as in Fig. VII. I then knit a line of loops with attendant penetration by them of the strip 5; and, after transferring loops from alternate needles N and doubling them with the loops on adjacent needles to form the picot course 6, proceed with the knitting of the remaining half 8 of the welt fabric as in Fig. VIII. The next step consists in closing the welt 3 with the aid of the welt bar shown at B; and I thereupon finally knit the leg and foot portions 2 and 3 of the stocking in the usual manner.

To produce the stocking of Figs. III and 25 IV, I proceed after the manner shown in Figs. X-XIII, i. e. I first knit half the length $7a$ of the welt fabric on the needles N of the knitting machine as in Fig. X, and then impale one edge of the elastic strip material $5a$ on the said needles as in Fig. XI. I thereupon form a course $6a$ of picot loops as before, with incident penetration by said loops, of the elastic strip material $5a$. Upon accomplishment of the foregoing I knit the remaining 50 half $8a$ of the welt fabric as in Fig. XII; then close the welt as in Fig. XIII to include the elastic garter material $5a$ within its fold; and finally, I knit the leg and foot portions in direct continuation to complete the blank.

To produce the stocking of Fig. V, I impale the elastic garter material $5b$ on the needles of the knitting machine above the nibs of the sinkers S, and immediately proceed with the knitting of the leg portion after the formation of the line of picot juncture loops.

When the selvage edges of the stocking blanks, made under either of the above described methods, are superposed upon one another and seamed after common practice in 55 the art, it is evident that the ends of the strip garter material will, as a matter of course, be joined as the over edge stitching is run past the welt.

Although I have herein specifically described my invention in connection with full fashioned stockings, it will be evident to those skilled in hosiery manufacture that the same may be embodied, with attainment of like 60 advantages, in seamless stockings as well as in short or men's hose.

Having thus described my invention, I claim:—

1. As a new article of manufacture, a knit 65 stocking with a welt top, and an elastic garter

with the edge thereof attached at the fold of the welt.

2. As a new article of manufacture, a knit stocking with a welt top, and an elastic garter attached through penetration of one of its 70 edges by the course of fabric loops along the fold of the welt.

3. As a new article of manufacture, a knit stocking with a welt top, and an elastic garter attached through penetration of one of its 75 edges by a course of picot loops along the fold of the welt.

4. As a new article of manufacture, a knit stocking with a welt top, and an elastic garter concealed within the welt and having its edge 80 attached at the fold line of the said welt.

5. As a new article of manufacture, a knit stocking with a welt top, and an elastic garter concealed within the welt, the said garter being attached through penetration of one of its 85 edges by the course of the fabric loops along the fold of the welt.

6. The method of making top welt stocking, which comprises impaling one edge of a length of elastic strip material on the needles 90 of a knitting machine; knitting half the length of the welt fabric with the elastic strip material maintained depressed on the needle shanks below the knitting level; then raising the elastic strip material to the knitting 95 level; then knitting the remaining half of the welt fabric; then turning the welt; and finally knitting the leg and foot portions of the stocking in the usual manner.

7. The method of making a garter top welt 100 stocking, which comprises impaling one edge of a length of elastic strip material on the needles of a knitting machine; then knitting half the length of the welt fabric while maintaining the elastic strip material depressed 105 on the needle shanks below the knitting level; then raising the elastic strip material to the knitting level; then forming a course of picot loops through the elastic strip material; then knitting the remaining half of the welt 110 fabric; then closing the welt; and finally knitting the leg and foot portions of the stocking in the usual manner.

8. The method of making a garter top 115 welt stocking, which comprises knitting half the length of the welt fabric on the needles of a knitting machine; then impaling upon the said needles one edge of a length of elastic strip material; then knitting the remaining 120 half of the welt fabric; then turning the welt so as to include the elastic strip material within the fold of the welt; and finally knitting the leg and foot portions of the stocking in the usual manner.

9. The method of making a garter top welt 125 stocking, which comprises knitting half the length of the welt fabric on the needles of a knitting machine; then impaling upon the said needles one edge of a length of elastic strip material; then knitting a course of picot

loops to penetrate the elastic strip material; then knitting the remaining half of the welt fabric; then closing the welt so as to include the elastic strip material within the fold of the welt; and finally knitting the leg and foot portions of the stocking in the usual manner.

In testimony whereof, I have hereunto signed my name at Lansdale, Pennsylvania, this 13th day of August, 1931.

EMIL J. BERGER.
